UNITED STATES PATENT OFFICE.

HERBERT II. HENNEGGIN, OF ST. LOUIS, MISSOURI, ASSIGNOR TO THE NATIONAL MOTOR COMPANY, OF SAME PLACE.

DESIGN FOR A GAS-ENGINE FRAME.

SPECIFICATION forming part of Design No. 31,807, dated November 7, 1899.

Application filed October 16, 1899. Serial No. 733,829. Term of patent 7 years.

To all whom it may concern:

Be it known that I, HERBERT II. HENNEGGIN, of the city of St. Louis, State of Missouri, have invented and produced a new and original Design for a Gas-Engine Frame, of which the following is a full, clear, and exact description, reference being had to the accompanying drawings, forming a part hereof.

Figure 1 is a side elevation of my design. Fig. 2 is a plan view thereof. Fig. 3 is an end elevation.

The leading or material feature of my design consists of a rectangular body located intermediate of two cylindrical bodies, with the latter in axial alinement.

1 indicates the rectangular body located intermediate of the two hollow cylindrical bodies 2, which latter are placed in axial alinement. Projecting from one of the vertical sides of the said rectangular body 1 is a horizontal cylindrical hollow projection 3, and directly beneath said hollow projection 3 is a

smaller horizontal cylindrical hollow projection 4, while on each side of said projection 4 is a smaller cylindrical projection 5. At 25 the inner end of each hollow cylindrical body 2 is a smaller cylindrical projection 6, which extends in a direction parallel with the hollow cylindrical projection 3.

At the outer end of each hollow cylindrical body 2 and secured to the base thereof is a lateral extension 7, which is L-shaped in cross-section and which projects a greater distance at one side of the said body than at the other side thereof. 35

I claim—

The design for a gas-engine frame, substantially as herein shown and described.

In testimony whereof I affix my signature in presence of two witnesses.

HERBERT II. HENNEGGIN.
